UNITED STATES PATENT OFFICE.

JAMES LEE SCOGGIN AND JOHN ROWE DEAN, OF GRAND SALINE, TEXAS,
ASSIGNORS OF ONE-HALF TO OWEN P. PYLE, OF MINEOLA, TEXAS.

PLOW.

SPECIFICATION forming part of Letters Patent No. 764,383, dated July 5, 1904.

Application filed September 23, 1903. Serial No. 174,347. (No model.)

To all whom it may concern:

Be it known that we, JAMES LEE SCOGGIN and JOHN ROWE DEAN, citizens of the United States, residing at Grand Saline, in the county 5 of Van Zandt and State of Texas, have invented a new and useful Plow, of which the following is a specification.

This invention relates to plows; and it has for its object to provide a device of this class 10 which shall possess superior advantages in point of simplicity, durability, and general efficiency.

Our invention relates particularly to an improved construction of a standard and a landside connected therewith and a stock connected with the landside at the point thereof for the purpose of supporting an earth-engaging plow, which may be of the bull-tongue type or any other sharp-pointed plow.

The invention further consists in the combination, with said standard and landside, of a pair of laterally-extending prongs, which may be detachably connected therewith and which are for the purpose of carrying not 25 only a pair of laterally-extending wings or blades, whereby the device may be converted into a wing-plow or lister, but which will also be adapted to support a pair of turning-plows, one or both of which may be used at any one 30 time, according to the work that is to be performed.

With these and other ends in view our invention consists in the improved construction, arrangement, and combination of parts, which 35 will be hereinafter fully described, and particularly pointed out in the claims.

In the accompanying drawings, Figure 1 is a perspective view showing the standard, the landside, and the stock of our improved plow. Fig. 2 is a perspective view of one of the frogs. Fig. 3 is a horizontal sectional view showing the device with one of the frogs in position. Fig. 4 is a front elevation showing the device with the frogs and the wings in position. Fig. 5 is a perspective detail view of one of the turning-plows. Fig. 6 is a top plan view showing the device with the frog, the wing, and the turning-plow in position on

one side thereof. Fig. 7 is a sectional view taken on the line 7-7 in Fig. 6.

50

Corresponding parts in the several figures are indicated by similar numerals of reference.

The landside 1, which forms the base of our improved plow, is secured at the lower end of 55 a standard 2, which latter is comparatively narrow and which terminates at its lower end in a web 3, whereby in spite of the comparative narrowness of the standard 2 great strength and rigidity is attained. The landside is provided at its front end and on its upper side with a pair of triangular flanges 4, which extend upwardly from but do not project beyond the side edges of the landside. These flanges constitute a toe between which and the point 60 of the toe is pivoted a plate 5, having a pair of upwardly-extending side members 6, which are spaced apart, as shown, but which do not extend beyond the limit of the width of the landside. The side members 5 include between 65 them the standard 2, and they at their upper ends are curved rearwardly, as shown at 7, said rearwardly-curved members being provided with notches 8. The standard 2 is provided with a perforation or keyhole 9, which 70 permits of the insertion of a key 10 through the keyhole 9 and through alining notches 8 in the upper edges of the members 7, thereby enabling the latter and the side members 6 75 with the plate 5, which together constitute 80 the stock of the plow, to be adjusted at any angle to which the said stock may be tilted. The side members 6 of the stock being spaced apart as shown will admit of the connection 85 therewith of a plow of any desired pattern, which may be secured in position by means of an ordinary heel-bolt, and such plow when mounted in operative position may be tilted to any extent within the limits of the construction of the device in order to enable it 90 to engage the ground at any desired depth. It will be seen that by the construction described none of the parts supported upon the landside are permitted to extend beyond the edges of the latter and will consequently not 95 interfere with the free and perfect operation

of the device. The sides of the standard are provided with offsets or enlargements 11 on opposite sides thereof, said offsets being preferably integral with the standard, the landside, and with the webbing, which serves to strengthen and reinforce these parts. The offsets 11 have curved rear edges which are concentric with recesses 12, formed in the under side of the plow-point at the front end 10 of the landside. The curved or segmental rear edges of said plates 11 are provided with undercut grooves 13, the purpose of which will be presently set forth.

The frogs or supporting members, which 15 are constructed alike save that they are constructed in right and left hand patterns for the opposite sides of the plow, are each composed of two members, one of said members being a plate 14, provided with a laterally-extending lug 15 at its pointed front end, said lug being adapted to engage the recess 12 of the plow-point at one side thereof, said plate 20 14 being of a length to extend almost to the undercut rear edge of the offset 11. The plate 25 14 is, moreover, provided with a laterally-extending flange 16, having a perforation 17, through which extends the head 18 of a bolt 19, which is bent or curved adjacent to the said head, so that after extending through the 30 perforation 17 it will extend in a rearward direction underneath the plate or flange 16. The other member of the frog or supporting device consists of a body 20, having side flanges 21, engaging the upper and lower edges of the 35 plate 14. The body 20 is also provided at its front end with a lateral outwardly-extending arm 22, terminating in a head 23, having a bolt-hole 24. The rear end of the body 20 has an inwardly-extending flange 25, provided with 40 a beveled groove 26, adapted to engage one of the undercut grooves 13 at the rear edges of the offsets 11. The body 20 is also provided on its inner side with a longitudinal groove 27 for the passage of the bolt 19, which extends 45 through an opening 28 at the rear end of the body and is provided with a tightening-nut 29. In order to attach one of these frogs or supporting devices to the side of the plow at which it belongs, it is only necessary to adjust 50 just the lug 15 in the notch 12 at the appropriate side of the plow-point. By loosening the nut 29 of the bolt 19 the body member 20 may then be so adjusted as to place the flange 25, having the groove 26, in engagement with 55 the undercut groove 13 of the offset 11, when by tightening the nut the members of the supporting device will be tightly drawn together, thus effecting a very secure attachment of the supporting device with relation to the body 60 of the plow. It will, moreover, be observed that this attachment is capable of a comparatively wide range of adjustment, inasmuch as by simply loosening the nut 29 the supporting device may be turned upon the lug or 65 stud 15 as a pivot, the rear end of said sup-

porting device being placed in engagement with any desired portion of the groove at the rear edge of the offset 11, the head of which latter is the only limit to the extent of adjustment of this part of the device. 70

The wing-blades 30, which are used in connection with the supporting device of our invention, are of ordinary construction and are each provided with two bolt-holes 31 and 32. The bolt-hole 31 is for the reception of the 75 bolt 19, which is placed in engagement therewith prior to its connection with the slideable member of the supporting device. An ordinary short bolt 33 extends through the bolt-holes 32 and 24, as shown. It is obvious that 80 the wings when in position serve to some extent to brace the members of the supporting device with relation to each other, and there being no forward or outward strain upon the wing-plates at any time the connecting means 85 hereby shown will be found to be thoroughly efficient and durable.

The turning-plows used in connection with our invention are composed of moldboards 35 of ordinary construction, which are provided 90 at their inner sides with vertically-disposed supporting-plates 36 and at the rear ends of the latter with a transversely-disposed supporting-plate 37, provided at their lower edges with notches 38, adapted to engage the 95 rear ends of the bolts 19. The front edges of the said plows are also provided with forwardly-extending lugs 39, which consist of plates suitably secured upon the under sides 100 of said plows. In order to mount the turning-plows for active operation with relation to the device, it is only necessary to loosen the nuts 29 at the rear ends of the bolts 19. The notches in the lower edges of the transverse plates 37 are then placed in engagement 105 with the bolt in rear of the frog, and the lugs 39 are then inserted under the upper edges of the wing-plates and the nuts 29 are tightened, thus securing the said turning-plows firmly 110 in operative position. When thus adjusted, it will be seen that the supporting-plates 36 of the turning-plows abut against the sides of the offsets 11 of the standard, while the lugs 39, engaging under the upper edges of the 115 wing-blades, serve to maintain the said plows very securely in position, the main support, however, being afforded by the rear supporting-plates 37, the notches of which directly engage the bolts and nuts, whereby a firm attachment is attained. 120

From the foregoing description, taken in connection with the drawings hereto annexed, the operation and advantages of our improved plow will be readily understood by those skilled in the art to which it appertains. 125

The plow may be adjusted and adapted to be used in a variety of different ways and for a variety of purposes. Primarily the standard, landside, and stock may be used with an ordinary bull-tongue or with an ordinary 130

wing-blade or, in fact, with almost any ground-engaging point of ordinary construction. In addition to this wing-blades may be attached to either or both sides of the plow by means of the frogs or supporting devices herein described, and said wing-blades may be used either independently or in connection with the turning-plows. We are thus enabled to produce either a right-hand or a left-hand turning-plow or, if preferred, a lister. It is also obvious that the relative sizes and shapes of the attachments may be varied to a great extent within the scope of our invention. It will further be noticed that no matter what may be the nature of the attachment or attachments used in connection with our device such attachments may be set at any desired angle or inclination whereby the ground will be engaged at any requisite angle to cause the implement to enter to any desired depth.

Having thus described our invention, we claim—

1. In a plow, a landside, a standard thereon, a pair of spaced plates extending upwardly from the point of the landside, with their outer edges in the planes of the edges of the latter, said plates combining to form a toe at the point of the landside, and a blade-supporting stock pivotally mounted between the members of the toe and comprising a pivoted plate and spaced side members engaging opposite sides of the standard.

2. In a plow, a landside, a standard supported thereon, and web connecting and bracing said landside, a standard, and offsets on opposite sides of the standard having segmental rear edges.

3. In a plow, a landside, a standard for the same, notches in the under side of the point of the landside, offsets on opposite sides of the standard having segmental undercut rear edges concentric with the notches in the point, supporting devices comprising members adapted to engage, respectively, the notches at the point and the undercut grooves of the offsets, and connecting and tightening means for said members.

4. In a plow, a landside, a standard supported thereon, notches in the under side of the point of the landside, supporting devices pivotally connected with said notches, and means for connecting said supporting devices adjustably with the sides of the standard.

5. In a plow, a landside, a standard supported thereon, supporting devices connected pivotally with the point of the landside, means for connecting said supporting devices adjustably with the sides of the standard, and a central supporting device connected pivotally with the point of the landside and adjustably with the standard.

6. In a plow, the combination with a landside and a standard supported thereon, said landside being provided at the point thereof

with notches and said standard being provided on opposite sides with offsets having segmental undercut rear edges concentric with the notches in the landside, of supporting devices comprising plates having lugs engaging the notches in the landside, and outwardly-extending flanges having bolt-holes, bolts extending through said holes and bent rearwardly, body members having flanges engaging the said plate and provided with outwardly-extending arms and with rear flanges engaging the undercut edges of the segmental offsets upon the standard, said body-plates having means for the adjustable connection of the rear ends of the bolts, nuts for clamping the said supporting devices in operative position, and blades mounted upon the said supporting devices.

7. In a plow of the class described, a landside, a standard supported thereon, offsets on opposite sides of said standard having segmental undercut rear edges, a blade-supporting stock having pivotal connection with the point of the landside and adjustable connection with the standard, blade-supporting devices having pivotal connection with the point of the landside and adjustable connection with the undercut segment plates or offsets upon the sides of the standard, and earth-engaging plow members mounted upon the said supporting devices.

8. In a plow of the class described, a landside, a standard supported thereon and a blade-supporting stock connected pivotally with the point of the landside and adjustably with the standard, blade-supporting members connected pivotally with opposite sides of the landside and standard, wing-blades supported on said devices, and turning-plows having lugs at their front edges engaging under the upper edges of the wing-blades and provided with transverse supporting means engaging the blade-supporting devices.

9. The combination with a plow, of a blade-supporting device comprising two slidably-connected members adapted to engage one side of the plow-frame and a connecting and tightening bolt, said members being provided, respectively with an outwardly-extending plate and an outwardly-extending arm, and a wing-blade connected with the outwardly-extending arm by an ordinary connecting-bolt and with the outwardly-extending plate by means of a bolt which is bent rearwardly and constitutes the connecting-bolt for the members of the supporting device.

10. The combination with a plow-frame, of a blade-supporting device connected pivotally and adjustably with the side of said plow-frame, said supporting device comprising two connected members, one of which is provided with a laterally-extending flange and the other with a laterally-extending arm, a bolt, bent close to the head thereof, said bolt being extended through a perforation in the flange ex-

tending from one member and thence rearwardly through the other member, and a nut upon said bolt whereby the said members may be drawn tightly together.

- 5 11. In a plow of the class described, the combination of the plow-frame, a supporting device comprising two members, one of which has a lug and the other of which has a flange provided with a beveled groove, means upon 10 the plow-frame to be engaged by said lug and grooved flange, and means for tightening the said supporting members together to thereby connect the said supporting device pivotally and adjustably with relation to the plow-frame.

- 15 12. In a plow, a blade, a supporting device comprising two connected members, one of said members having a laterally-extending flange and the other a laterally-extending arm, 20 a connecting-bolt extending through the flange of the one member and bent rearwardly through the other member, a nut upon said bolt for tightening the members together, and a wing-blade supported upon the flange and

the arm of the members of said device and 25 secured to the arm by means of an auxiliary connecting-bolt.

13. In a plow, the combination of the plow-frame, a supporting device connected pivotally and adjustably with the side of said frame, 30 and consisting of two connected members and a tightening-bolt connecting the same, a wing-blade supported upon said device, and a turning-blade having a longitudinal supporting-plate engaging the standard of the plow-frame, 35 a transverse supporting-plate having a notch engaging the connecting-bolt of the members of the supporting device, and a forwardly-extending lug engaging under the upper edge of the wing-blade.

In testimony that we claim the foregoing as our own we have hereto affixed our signatures in the presence of two witnesses.

JAMES LEE SCOGGIN.
JOHN ROWE DEAN.
